UNITED STATES PATENT OFFICE.

WILLIAM F. BOSSERT AND JOHN C. EDWARDS, OF UTICA, NEW YORK, ASSIGNEES TO SIGNAL ACCESSORIES CORPORATION, OF UTICA, NEW YORK, A CORPORATION OF NEW YORK.

DIRECTIONAL TRACK CONTACTOR.

Application filed August 14, 1922. Serial No. 581,678.

This invention relates to a new directional track contactor, and more specifically to mechanism for controlling electric circuits adapted to be actuated by the contact of a 5 passing locomotive or car wheel, which mechanism when primarily actuated upon the passing of a train in either direction, will not be affected by subsequent contacts of a car or locomotive wheel until the entire 10 train has passed beyond the zone of the device, thereby adapting the device for use upon single track railways.

In a general way, the invention comprises the combination with a railway track of a 15 wheel contact mechanism attached to a rail section or the ties thereof, and arranged to be actuated by the foremost wheel only of the passing train, and being provided with a mechanical time release attachment by 20 which subsequent operations by the succeeding wheels are avoided until the train has passed beyond the zone of the device. The invention utilizes or embodies a circuit-closing means positioned directly in line with 25 the contact point, and having mechanically operable connection to the contact device.

The main object of the invention is to provide circuit-controlling means of the character described, adapted to be actuated 30 in either direction from a normal position by an impulse received from the wheel of a passing train to thereby indicate at some more or less distant point, the passage of such train, and the direction of its movement.

A further object is to provide a device which may be readily installed and attached 35 to a railway track without disturbing the ties or rails from their original position, and which is economical in construction and maintenance, and efficient and reliable in operation, and durable in service.

Other objects and advantages relate to the details of construction, form and arrangement of the parts, all as will more fully appear from the following description, taken in connection with the accompanying drawings, in which:—

Figure 1 is a side elevation of the wheel 50 contact device and power-transmitting shaft, in combination with a sectional view through the instrument box.

Figure 2 is a view showing an end elevation of the wheel contact device and the method of applying the same to a track. 55

Figure 3 is a top plan view of the instrument box with the cover removed.

Figure 4 is a section on line 4—4, Figure 3.

Figure 5 is a section through the pawl- 60 supporting and actuating mechanism.

Figure 6 is a sectional view through the commutator and the contact devices associated therewith.

Figure 7 is a section through the instru- 65 ment box taken on line 7—7, Figure 1.

Figure 8 is an elevation of the time release mechanism utilized in connection with the invention.

Figure 9 is a vertical sectional view 70 through the mechanism of Figure 8.

Figure 10 is an elevation partially in section of the rocking levers for actuating the weight utilized in connection with the time release mechanism. 75

Referring to the drawings, the invention is illustrated in connection with a railway track, including a rail —1— with the wheel —2— moving thereon, and the ties —3— for supporting the rail. 80

The contact trip —4—, as illustrated, is carried by a contact lever —5—, the latter being provided with an angular or squared opening fitting a squared portion of the shaft —7—, and adapted to convey any 85 movement of the contact lever —5— to the mechanism of the instrument box herein-after described. Preferably, the operating shaft —7— includes a flexible insulated joint —8— of any suitable well known construction. The other end of the shaft —7— may be provided with a squared portion, as indicated, which is passed through the central portion of a yoke —9— and through the axis of a segment gear —10—, the latter 90 adapted to actuate pinions —13— mounted upon a pair of oppositely disposed shafts —30— extending longitudinally of the instrument box —31—.

The opposite ends of the yoke —9— are 100 each equipped with a clevis —11— having a portion disposed within and engaged with the respective springs —12—, which springs support the clevises in proper position. The

lower ends of the springs are maintained in predetermined relation to the instrument box —31— in any suitable way, as by providing the box with recesses —14— within which the lower ends of the springs are adapted to project. These springs are of such form and size as to normally maintain or tend to maintain the yoke in a balanced or equilibrium position, as indicated in Figure 4.

10 The shafts —30—, as indicated, extend longitudinally of the instrument box —31— and are in substantial parallelism with the operating shaft —7—, and as stated, at one end are equipped with pinions —13—.

15 A framework —15— is arranged within the instrument box —31— for supporting the parts already described, and those now about to be described.

This framework comprises an upright 20 —16— in which the end of the shaft —7— may be journaled at a point beyond the mounting of the segment gear —10— and in this upright —16— at opposite sides of the instrument box are mounted the forward 25 ends of the shafts —30— upon which the pinions —13— are mounted for co-operative engagement with the segment gear —10—. The opposite ends of the shafts —30— are mounted in an upright —17— of the said 30 framework, which upright may be spaced a proper distance from the adjacent end of the instrument box to permit mounting upon the said shafts between the upright and the adjacent wall of the box, of a pair of 35 ratchets —18— and a pair of weight-operating levers —50— journaled at 19 on shafts —30—.

Upon the shafts —30— between the uprights —16— and —17— are mounted cylindrical commutators —20—, each commutator comprising an insulating cylinder, and a series of contacts —26— which may be of the form shown in Figure 6, and adapted to form a circuit closing medium between the springs, brushes or contacts —21— which project, or may project, downwardly from an insulating cover —22— secured to the upper ends of the uprights —16— and —17— and forming with the said framework a partial casing for the commutator —20—. These insulating covers —22— may carry suitable terminals —23— to which the wiring systems may be secured, the wires being conveyed from the instrument box through 55 an outlet —6— and a flexible conduit —24— which may carry the wires to any suitable more or less distant point where the signals are to be produced and interpreted.

It will be obvious that if the commutator 60 and the contacts —21— are normally in the relative position shown in Figure 6, that rotation of the shaft —30— through substantially a quarter turn, or an arc of 90 degrees, will bring the commutator contact 65 —26— into a position to close the circuit be-

tween the oppositely disposed fingers or contacts —21—, thereby effecting the production of a predetermined signal, should that be desired. The mere closing of the circuit indicates the movement of contact trip —4— 70 as by the wheel of a passing train. The ratchets —18— mounted upon respective shafts —30— are each free to rotate in one direction, but are normally prevented from return rotation by the pawls —27— pivoted 75 at —28— upon the framework —15— and for the purpose of moving said pawls from engagement with the respective ratchets, the pawls may have their inner ends connected by a pair of links —29—, one of said links 80 having a pivotal connection to the other pawl, and said links having a common pivot —60— on a box-like structure —61— and which may be depressed against the action of the supporting spring —32— to move 85 said pawls from engagement with their respective ratchets, and thereby permit return movement of either ratchet and either of the shafts —30— to its original position, as actuated by the balancing springs —12—. 90

This depression of the box-like structure —61— is effected at a delayed and substantially predetermined time through the medium of a weight —33— mounted upon an arm —34— rotatably journaled on the flange 95 —36— of a gear wheel —37—, which wheel is in turn rotatably mounted on a shaft —35—, the arm —34— being provided with a pivoted pawl —47— that engages the teeth of the gear —37— so as to rotate said gear —37— as the weight —33— lowers or falls. The gear —37— is in mesh with gear teeth —39— formed integrally upon the shaft —36— which shaft has mounted thereon an auxiliary time release gear —40— 100 pinned to the shaft for rotation therewith, and having its peripheral teeth in engagement with gear teeth —41— formed integrally with the shaft —35—. Mounted on the flange —65— of the gear —40— is one 110 member of an escapement mechanism for causing a step by step movement of the time release mechanism. This escapement mechanism, as stated, consists of an oscillatory ring —42— having a pair of inwardly projecting 115 teeth or lugs —43— and —44— which are adapted to engage the teeth upon the periphery of an escapement wheel —43'— keyed to shaft —35—, so as to rotate therewith. As the escapement wheel —43'— is 120 rotated through the rotation of shaft —35— by means of the gears —40— and —37— and the gear teeth —39— and —41—, the teeth upon the escapement wheel —43'— will come into contact with the pawls or teeth —43— and —44— upon the interior of the oscillating ring —42— and the teeth upon the escapement wheel —43'— by alternate engagement with the pawls —43— and —44— will 125 move the pawls to thereby effect oscillating 130

movement of the ring —42—, whereby a step by step rotation of the gear —37— is permitted to allow in like manner a step by step downward movement of the arm —34— and the weight —33—, such movement continuing until the lever arm —46— upon the pawl —47— comes into contact with the adjustable stop —48— whereupon the pawl —47— is moved from engagement with the teeth of the gear —37— and the weight —33— falls and strikes the box-like structure —61— causing the pawls —27— to be moved from engagement with their respective ratchet wheels —18— thereby permitting the springs —12— to move the operating mechanism to its original position.

The mechanism for raising the weight —33— and its lever arm —34— to the elevated position from which it gravitates in a step by step movement, as described, consists of the lever arms —50— which, as shown, may be of jointed form so as to be capable of returning to their original position after the weight —33— has fallen.

By reference to Figure 10, it will be seen that the weight —33— is normally in its lowermost position resting upon the box-like structure —61—, this being the normal and inoperative position of the structure. Upon rotation of either of the shafts —30— the jointed arm carried by the respective shaft will be moved thru the arc illustrated in Figure 10 to the position shown in dotted lines, and during such rocking movement, the end of the lever —50— will contact with the weight —33— and throw it upwardly to the position shown in dotted lines, Figure 10.

The weight will then begin to move downwardly while the shafts —30— are locked in stationary position, and will gradually move to the position where the releasing member —46— strikes the stop —48— and the weight drops to release the shaft —30— from its locked position, and permit its return through the action of one of the springs —12—.

The instrument housing —31— may be supported, as indicated, between two ties —3— to which it is connected in any suitable way as by means of the angular straps —70—. These straps may be connected to the housing in any suitable manner or may consist of a single strap of metal extending beneath the housing up the sides thereof and then bent outwardly across the ties. The frame —15— including the uprights in which the rotary parts are journaled may be secured to the housing in any suitable manner, as by bolts not shown, or otherwise.

This housing may include a cover —71— forming a water-tight joint with the other portions of the housing in any suitable manner, as by interposed packing, and may be securely fastened in position as by locking strap —72—.

The operation of the device in a general way is as follows:

When the foremost wheel of a train strikes the contact trip —4— it will turn the contact lever —5— approximately 25 to 30 degrees 70 in the direction in which the wheel is moving, thereby operating or rotating the shaft —7— through a similar arc to operate the yoke —9— and the adjusting clevises —11— and springs —12— the extent of depression of 75 the springs under opposite directional movements of the shaft —7— depending upon their adjustment with the clevises —11—. The segment gear —10— attached to the shaft —7— will be revolved by movement 80 of the shaft, and will transmit motion to one of the pinions —13—.

It will be understood that movement of the segment gear in one direction operates but one of the pinions, and that movement 85 of the segment gear in the opposite direction will actuate solely the other pinion, thus making the instrument absolutely directional.

The revolving motion of the segment gear —10— and the particular pinion —13— attached to its shaft —30— will transmit this motion to the commutator —20—, the time release operating lever —50— and the ratchet wheel —18—, which ratchet wheel will be maintained in the position to which it is 95 moved by its respective pawl —27— until released, as described. The movement of the shaft —30— will raise the time release operating lever —50— together with operating weight —33— to a predetermined height, 100 whereupon the weight —33— will set in motion the mechanical time release hereinbefore described, and when the weight has lowered to the point where the lever arm —46— contacts with the adjustable stop 105 —48— the weight —33— will drop suddenly upon the box-like structure —61— releasing the pawls —27— from engagement with their respective ratchets —18— and permitting springs —12— to return the segment gear, 110 the shaft 30 and parts carried thereby to a normal starting position.

Altho we have shown a specific construction as illustrative of a mechanism operable for our purpose, and which may include details of form and construction preferred at present, we do not desire to limit ourselves to the particular relation of parts or their details of form, construction and arrangement, as various changes may be made in 120 each without departing from the invention as set forth in the appended claims.

I claim:

1. A track contactor comprising a shoe, a rotary shaft actuated thereby, a pair of pinions selectively actuated by movement of said shaft in opposite directions, and movable contacts actuated by said pinions.

2. A track contactor comprising a shoe, a rotary shaft actuated thereby, a pair of pin- 130

- ions selectively actuated by movement of said shaft in opposite directions, movable contacts actuated by said pinions, and ratchets actuated by said pinions.
3. A track contactor comprising a shoe, a rotary shaft actuated thereby, a pair of pinions selectively actuated by movement of said shaft in opposite directions, movable contacts actuated by said pinions, ratchets actuated by said pinions, said operating levers actuated by said pinions.
4. A track contactor comprising a shoe, a rotary shaft actuated thereby, a pair of pinions selectively actuated by movement of said shaft in opposite directions, movable contacts actuated by said pinions, ratchets actuated by said pinions, operating levers actuated by said pinions, a weight-operated time release mechanism, and a weight-actuated by said levers.
5. A track contactor comprising a shoe, a rotary shaft actuated thereby, a pair of pinions selectively actuated by movement of said shaft in opposite directions, movable contacts actuated by said pinions, ratchets actuated by said pinions, operating levers actuated by said pinions, a weight-operated time release mechanism, a weight actuated by said levers, pawls engaged with said ratchets, and means operated by said weight for moving said pawls from engagement with said ratchets.
6. A track contactor comprising a contact member, a rocking shaft actuated thereby, a segment gear carried by said shaft and pinions selectively actuated by said segment gear in accordance with the direction of rocking of said shaft.
7. A track contactor comprising a contact member, a rocking shaft actuated thereby, a segment gear carried by said shaft, pinions selectively actuated by said segment gear in accordance with the direction of rocking of said shaft, shafts actuated by said pinions, and contacts brought into circuit-closing relation by rotation of said last named shafts.
8. A track contactor comprising a contact member, a rocking shaft actuated thereby, a segment gear carried by said shaft, pinions selectively actuated by said segment gear in accordance with the direction of rocking of said shaft, shafts actuated by said pinions, contacts brought into circuit-closing relation by rotation of said last named shafts, and ratchets rotating with said last-named shafts.
9. A track contactor comprising a contact member, a rocking shaft actuated thereby, a segment gear carried by said shaft, pinions selectively actuated by said segment gear in accordance with the direction of rocking of said shaft, shafts actuated by said pinions, contacts brought into circuit-closing relation by rotation of said last named shafts.
10. A track contactor comprising a contact member, a rocking shaft actuated thereby, a segment gear carried by said shaft, pinions selectively actuated by said segment gear in accordance with the direction of rocking of said shaft, shafts actuated by said pinions, contacts brought into circuit-closing relation by rotation of said last named shafts, ratchets rotating with said last named shafts, and pawls for engagement with said ratchets.
11. A track contactor comprising a contact member, a rocking shaft actuated thereby, a segment gear carried by said shaft, pinions selectively actuated by said segment gear in accordance with the direction of rocking of said shaft, shafts actuated by said pinions, contacts brought into circuit-closing relation by rotation of said last named shafts, ratchets rotating with said last named shafts, pawls for engagement with said ratchets, and means for moving the pawls from engagement with the ratchets.
12. In a track contactor a time release mechanism operated solely by weight.
13. In a track contactor an instrument actuated by a passing train and means for maintaining said instrument in its actuated position.
14. In a track contactor an instrument actuated by a passing train and means for maintaining said instrument in its actuated position, and a time release mechanism for releasing said instrument from its actuated position after a substantially predetermined period.
15. A track instrument including a wheel contact member adapted to receive its operating impulse from the foremost wheel of a passing train, said instrument including a locking device that eliminates contact of said member with the succeeding wheels of a passing train.
16. A track instrument including a wheel contact member adapted to receive its operating impulse from the foremost wheel of a passing train, said instrument including a locking device that eliminates contact of said member with the succeeding wheels of a passing train, and a time release mechanism permitting return of said instrument to starting position.
17. A track instrument including a wheel contact member adapted to receive its operating impulse from the foremost wheel of a passing train, said instrument including

a locking device that eliminates contact of said member with the succeeding wheels of a passing train, a time release mechanism permitting return of said instrument to starting position, and spring means for effecting such return.

18. A track contactor including mechanism actuated by a passing train and pawls and ratchets for holding said mechanism in 10 its actuated position.

19. A track contactor including mechanism actuated by a passing train, and pawls and ratchets for holding said mechanism in its actuated position, and a time release 15 mechanism for effecting movement of said pawls from engagement with the ratchets.

20. A track contactor comprising a contact member, a rocking shaft actuated thereby, a yoke actuated by said shaft, spring means supporting the opposite ends of said 20 yoke, a gear actuated by said shaft, a pair of longitudinal commutator shafts and gears on said commutator shafts meshing with the first-named gear, means for holding said commutator shafts in actuated position 25 after each actuation, and means for releasing said holding means after the lapse of a predetermined time.

In witness whereof we have hereunto set our hands.

WILLIAM F. BOSSERT.
JOHN C. EDWARDS.
